(57) **CLAIM**

The ornamental design for a faceted conoidal connector, as shown and described.

DESCRIPTION

FIG. 1 is a perspective view of the present invention;

FIG. 2 is a top plan view thereof;

FIG. 3 is a bottom plan view thereof;

FIG. 4 is a front side elevation view thereof;

FIG. 5 is a back side elevation view thereof;

FIG. 6 is a right side view thereof; and,

FIG. 7 is a left side elevation view thereof.

Any broken lines shown in the figures depict portions of the faceted conoidal connector and form no part of the claimed design.

1 Claim, 7 Drawing Sheets
